UNITED STATES PATENT OFFICE.

WILLIAM WARREN SHILLING, OF SHARON, PENNSYLVANIA.

WATER-TUBE-BOILER FURNACE.

SPECIFICATION forming part of Letters Patent No. 683,506, dated October 1, 1901.

Application filed January 31, 1901. Serial No. 45,468. (No model.)

To all whom it may concern:

Be it known that I, WILLIAM WARREN SHILLING, a citizen of the United States, residing at Sharon, Pennsylvania, have invented 5 certain new and useful Improvements in Water-Tube-Boiler Furnaces, of which the following is a specification.

My invention relates to water-tube-boiler furnaces of that class in which the furnace-wall is rectangular in cross-section, within which are confined two sets of horizontally-arranged boiler-heads connected by stacks of vertically-arranged water-tubes, the lower heads being supported upon fire-arches, below which are located the fire-chambers. 15

The invention is confined more particularly to the arrangement of the fire-brick, which is built in between the walls of the furnace and the water-tubes and in between each set of 20 tubes, around the lower ends of the same.

To this end the invention includes the arrangement of these bricks to provide a series of passages for the arising heated gases, the top of the passages being closed to deflect said 25 gases through the spaces between the tubes of each stack, the passages formed by the central tier of brick extending above the passages formed by the outside tiers.

The invention also includes means for reinforcing the boiler-heads.

The invention is illustrated in the accompanying drawings, in which—

Figure 1 is a vertical sectional view through a furnace embodying my invention. Fig. 2 is 35 a cross-sectional view. Fig. 3 is a plan view of one head-strengthening brace. Fig. 4 is an end view of the reinforcing-plate.

The furnace-wall, as shown in Fig. 2, is 40 rectangular in cross-section. Two fire-arches 12 extend from front to rear thereof, near the bottom of same, above the fire-chamber, which support the lower heads 34, connected by the stacks of tubes 5 6 to the upper heads 7 8, which in turn are connected up in the ordinary manner common in this class of furnaces. 45 Near the upper heads the spaces between the stacks of tubes 5 6 and the adjacent furnace-walls are closed by brick deflectors 9 10. The space between the stacks 50 of tubes is closed at the top by a brick arrester 11, built between the upper heads of the boilers.

Built between the lower portions of the tubes and the adjacent side walls of the furnace are two tiers of brick 12 13, with their bottoms flush with the upper faces of the lower boiler-heads. A central tier of brick 14 is built between the two stacks of tubes and extends a distance above the top of the tiers 12 and 13. Each of said tiers comprises a series 60 of vertical walls, between which are located vertical passages unobstructed throughout their entire extent, except at the top of the tiers, where they are closed by brick layers 15, 16, and 17. The layer 17, closing the central tier, is some distance above the layers 15 and 16, closing the outside tiers, so that the passages of the central tier extend to a greater height than the passages in said outside tiers. By this arrangement the heated gases arising 70 from the fire-chambers pass through the passages in said tiers of brick. The gases passing up through tiers 12 and 13 are arrested by layers 15 and 16 and forced to pass inwardly through the spaces between the tubes 75 of each stack. As these spaces are not of sufficient area to accommodate the entire volume of arising gases, the said gases pass through the same into the passages in the central tier of brick, commingling with the 80 gases arising directly from the fire through the passages therein. This volume of gas is arrested by layer 17 and forced to again pass through the spaces between the tubes of each stack to the space between each stack of 85 tubes and the adjacent furnace-walls. The deflectors 9 10 at the top of the tubes again deflect the gases inwardly through the spaces between the tubes of each stack, and the arrester 11 causes the gases to again pass outwardly. The tiers of brick not only serve to twice deflect the heated gases through the spaces between the tubes of each stack, but they form as well an absorbent medium to retain the heat about said tubes. 90

The boiler-heads used in this class of furnaces each have flat ends and a flat face, into which the tubes are secured. High pressure in these heads tends to bulge said flat parts outwardly. To counteract this action, I have 100 provided reinforcing-pieces. The reinforcing-pieces *a* for the flat faces of the boiler comprise flat bars designed to extend transversely of the part to be reinforced. The 95

bars are provided with bosses through which the bolts to secure the bars in position pass. These bosses are so disposed that they occupy the space centrally between four tubes, while 5 the web portions of the bars which connect the bosses occupy the space between two adjacent tubes. The bosses have extensions beyond the edge of the web portions of the bar which bear on the part to be reinforced, 10 and the ends of the bars are provided with like extensions. The bar thus forms a series of strengthening-arches. For the ends of the head the reinforcing-bars are made of angle-iron in substantially the form of the letter H, 15 the cross-pieces passing between the man-hole in said heads and the pipe-opening.

I claim—

In a water-tube-boiler furnace, the combination with the furnace-wall, and the two sets 20 of horizontally-arranged boiler-heads con-

nected by vertical stacks of tubes, of a central tier of brick built between the two stacks of tubes, and outside tiers of brick between each stack of tubes and the adjacent furnace-wall, all of said tiers having vertical passages 25 in the same, the passages in each tier being closed at the top of the latter, said central tier of brick extending above the top of the outside tiers whereby the ascending gases will be first deflected inwardly through the 30 spaces between the tubes of each stack and then outwardly through said spaces, substantially as described.

In testimony whereof I affix my signature in presence of two witnesses.

WILLIAM WARREN SHILLING.
